(57) **CLAIM**

The ornamental design for a dual slide rail rowing machine as shown and described.

DESCRIPTION

FIG. 1 is a perspective view of a dual slide rail rowing machine according to the present invention;

FIG. 2 is a front view of the dual slide rail rowing machine according to the present invention;

FIG. 3 is a rear view of the dual slide rail rowing machine according to the present invention;

FIG. 4 is a left-side view of the dual slide rail rowing machine according to the present invention;

FIG. 5 is a right-side view of the dual slide rail rowing machine according to the present invention;

FIG. 6 is a top view of the dual slide rail rowing machine according to the present invention; and,

FIG. 7 is a bottom view of the dual slide rail rowing machine according to the present invention.

The broken lines are for illustrative purpose only and form no part of the claimed design.
